UNITED STATES PATENT OFFICE.

LESTER R. WELLMAN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR A LIGHTING-FIXTURE.

50,539.

Specification for Design.

Patented Mar. 27, 1917.

Application filed December 30, 1916. Serial No. 139,975. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Lighting-Fixture, of which the following is the specification, reference being had to the accompanying drawing, forming part thereof.

The figure is a side elevation of a lighting fixture, showing my new design.

I claim:

The ornamental design for a lighting fixture, as shown.

LESTER R. WELLMAN.
